UNITED STATES PATENT OFFICE.

CLARENCE D. BALDWIN, OF NASHUA, IOWA.

METHOD FOR PILING LUMBER FOR DRYING PURPOSES.

Application filed December 3, 1923. Serial No. 678,367.

To all whom it may concern:

Be it known that CLARENCE D. BALDWIN, a citizen of the United States, residing at Nashua, in the county of Chickasaw and State of Iowa, has invented new and useful Improvements in Methods for Piling Lumber for Drying Purposes, of which the following is a specification.

In lumber camps and around sawmills, the lumber, as a rule, is not piled in order to provide for proper circulation of air in order that the lumber may be thoroughly seasoned. For instance, at present the lumber strips are placed too close together and are in register which causes the lumber to have unseasoned spots or sections and where the lumber is seasoned, it loses its shape. In fact, each piece of lumber is more or less irregular due to the seasoned and unseasoned places. Furthermore, in the old method there is no means afforded for draining off the water around the piles as well as no means being provided for binding the several piles together. Moreover, the tops of the piles are not properly covered to shed the water and, as before stated, as there is no means for draining off this water, the lumber is improperly seasoned.

In the present construction of piles and the method of arranging the lumber, the present invention has for its purpose to dispose the lumber in piles or tiers, thereby suitably supporting the lumber, there being ditches at the base of the piles to drain away the rain which may shed from the roof of the piles of lumber, thus avoiding the creation of steam and moisture.

Another purpose is to pile each layer of lumber at right angles to a preceding layer, the lumber of each layer being properly spaced and in staggered relation to the lumber of the preceding layer so as to insure a thorough circulation of air and permit of the evaporation of what little steam may exist, so that the lumber may be thoroughly seasoned throughout its length.

A still further purpose is to provide cleats which are designed to be disposed in staggered relation, not only with the lumber of each layer but staggered relatively to the cleats above and below so as to afford air circulating spaces between the lumber and to avoid unseasoned places in the lumber as in the old method.

A further purpose is to provide spaced lumber piles or tiers with certain of the

lumber bridging the piles at different locations, thereby acting as binders between the piles while the spaces between the piles insure a thorough circulation of air.

A still further purpose is to provide a roofing of a temporary character for the piles of lumber consisting in arranging a layer of boards equal distances apart with a second layer, the boards of which are arranged longitudinally parallel with the first layer and bridging the spaces between the first layer, the second layer of boards constituting lap boards to insure shedding the moisture, rain and snow. This roofing may extend a substantial distance beyond the rear of the pile and forwardly of the front thereof to insure shedding the rain so that it may drain off through the medium of the ditches at the base of the piles. Furthermore, by providing a roofing of this character, the spaces under the lap boards, that is, between the first layer of boards, constitute means to permit of the circulation and escape of air as it passes up through the pile.

It is to be understood that the particulars herein given are in no way limitative and that, while still keeping within the scope of the invention, any desired modifications of detail and desired proportions may be made according to the circumstances.

The invention comprises further features and combinations of parts to be hereinafter set forth, shown in the drawings and claimed.

In the drawings:

Figure 1 is a view in side elevation showing a suitable foundation of beams and cross blockings thereunder, there being piles of lumber thereon, each being arranged and constructed in accordance with the invention.

Figure 2 is a view in front elevation, showing the relation of the lumber and the staggered arrangement of cleats and more clearly showing the arrangement of the boards constituting the roof for the pile of lumber, showing the slope of the ground around the piles and also showing the ditches.

Referring to the drawings, 1 designates the cross blockings for the foundation beams 3, there being surrounding ditches 2 for the purpose of draining off the moisture, rain and snow. In fact, the cross blockings are arranged upon the surface of

the ground which is slightly inclined so that the roofing will be inclined for the purpose of draining off the rain.

- 5 The lumber 4 is disposed upon the cleats 6 in consecutive layers 5 suitably spaced, the lumber of one layer extending at right angles to the lumber of a preceding layer. Furthermore, the lumber of the various layers is in staggered relation with intervening 10 cleats 6. The cleats of one layer are in staggered relation with those of an adjacent layer. By disposing the lumber pieces and cleats in properly spaced positions and in 15 staggered relation, air circulating spaces are afforded to carry off what little steam may be created and permit of a thorough circulation of air for the purpose of thoroughly seasoning all parts of the lumber. Since the lumber pieces and cleats are staggered 20 as shown and set forth, it will be noted that no directly opposite parts of any one piece of lumber are covered, therefore all parts of the lumber will thoroughly season and thereby avoid irregular beams.
- 25 At intervals, certain of the timber cleats 7 bridge from one pile of lumber to another, acting as a binder between the piles, and since the several piles are spaced, the intervening spaces act to permit of a thorough 30 circulation of air between the piles to the roof. The air as it ascends to the roof will deflect and pass off through the spaces 8 between the first layer of boards 9 of the roof 10. These spaces 8 of the roof are covered 35 by the lap boards 11 which are disposed longitudinally and parallel with the first layer of roof boards. The roof boards protrude forwardly and rearwardly of the front and rear of the various piles of lumber, that is, 40 a substantial distance sufficient to shed the moisture, rain and snow into the ditches at the base of the pile. It will be noted that the various layers of lumber are at right angles to each other, that is, crosswise with 45 the cleats between the layers, there being cleats 12 between the roof and the upper part of the roof lumber pile, thereby preventing the crossed lumber from sagging and also insuring a solid bearing.
- 50 The tiers or layers of lumber are designed to have substantial intervening spaces, the side, front and rear faces of the pile of lumber being perpendicular so that the air may easily rise at the front, sides and rear 55 and at the same time circulate through the air spaces on the interior of the pile of lumber.

60 The body of each pile of lumber is designed to be of substantial width, preferably six feet wide, and, furthermore, the spaces between the several piles of lumber are to be of substantial size. The cleats are not to extend across the spaces between the several piles of lumber throughout their entirety, 65 only occasionally, and are located preferably

about six feet from the base. These bridging timber cleats act as binders between the piles of lumber, and those binding cleats above the first arrangement of cleats are to be substantially three feet above the preceding ones to insure a thorough circulation of air.

70 The piers 13 for the roof are to be substantially high, preferably twelve inches, and the boards of the roof are substantially 75 spaced to insure ample room for the boards to expand and contract. The second layer of boards of the roof cover the spaces between the first layer, certain spaces acting to carry off the air laterally and insure a circulation thereof. In arranging the lumber in piles of this character, the lumber is prevented from sagging between the spaces, thereby obviating irregular beams of lumber.

80 The first layer of cleats are directly 85 lengthwise in center of each tier or pile. The second layer of cleats are jogged in backward or forward positions either way, so that the inside edges of both cleats come directly in the center. Then the third layer 90 of cleats are jogged in backward positions directly over the first cleats so as to keep the cleats mismatched or staggered but the center of cleats over each separate tier, 95 whereby the entire height of lumber tier or pile with center edges of cleats is in a direct line perpendicularly.

100 The lumber is spaced, leaving cracks or spaces for air and all the layers thereafter are to be kept perpendicularly above the others so that said air spaces or cracks are kept directly open perpendicularly so steam can pass directly to the roof cleats between the layers of lumber. It is the purpose to 105 permit the steam to pass from between said lumber layers to the air spaces between the lumber tiers. *a* are the lumber tiers or piles and *b* are the air spaces between each tier of lumber. In carrying out this method, 110 caution must be exercised to keep the lumber tiers with their edges even above and below each other, so as not to interfere with the air circulation, as it is obvious that steam rises upwardly to the roof cleats. For this reason, the boards are disposed apart so air 115 can circulate sidewise of the lumber. It will be noted that the lumber is in piles, there being several piles to a volume, hence *c* are the spaces between the volumes, while *d* designate the binder cleats. As many volumes of lumber as are necessary can be attached or connected instead of one solid volume. This space between the volumes and also between the lumber tiers must be 120 kept open for the circulation of air so as to carry off the steam upwardly to the open roof.

125 The roof tier or construction must come directly over the cleats below in order to withstand the weight of the roof. The roof 130

is composed of lumber, one piece above the other, with cleats therebetween. Each board is spaced close enough to support the weight of the roof and prevent sagging of the pier boards. The cleats are of suitable thickness so air can pass lengthwise of the lumber pile directly through each roof pier. Blocks can be conveniently spaced two feet apart with crosswise blocks which permit of a greater 10 air space. In this way, air can pass four ways, so that the wind from any angle can pass through and under the roof and between and lengthwise of the open roof piers.

The cleats may be of suitable thickness, 15 width and length and are mismatched or staggered with the inside edges even. If wide cleats are used, they must lap a little in the center to take up bearing which would otherwise cause the weight of the 20 lumber to sag and kink between cleat spaces. As the wider cleats are mismatched, it gives a wide area and affords a bearing for the weight of the lumber above. As previously stated, in the old method, the cleats are disposed directly above each other, thereby 25 causing a solid wall without any air spaces.

Where the cleats are disposed directly above each other, it causes the lumber to season improperly, there being spots and mould at different points. By having free air circulation under the piles and through the same and sidewise, also lengthwise, from base to roof, there will be no spots and mould on the lumber at all. The lumber rests on base beams or piers crosswise of said beams. 30 35

The invention having been set forth, what is claimed is:

A method of seasoning lumber consisting in supporting the pile mounted on a foundation, disposing lumber layers, spacing the 40 lumber of the layers to insure circulation of air, staggeredly disposing cleats spacedly to further insure the circulation of air, spacing one pile of lumber from an adjacent pile, 45 also insuring a circulation of air, binding the several piles together, and then roofing the several piles, thereby additionally connecting the piles.

In testimony whereof he affixes his signature.

CLARENCE D. BALDWIN.
